WHISTLING CANE

Earl H. Pitney, Willmar, Minn.

Application December 16, 1938, Serial No. 246,150

1 Claim. (Cl. 135—47)

My invention relates to novelty canes or walking sticks and particularly to canes having sound-producing means incorporated therein.

Novelty canes have been made having means therewithin for producing a single sound or note responsive to suitable manipulation of the cane and it appears that a cane capable of producing respectively different sounds in succession would be desirable. Such a cane could readily be arranged for producing bird call imitations or other combinations of sounds involving two respectively different musical notes in succession.

An object of my invention is to provide a novelty musical cane capable of being manipulated to produce two sounds of respectively different characteristics in succession.

Another object is to provide such a cane capable of producing a sound of one characteristic responsive to placing longitudinal pressure on the cane and a sound of another characteristic responsive to removal of said pressure.

A further object is to provide such a cane of light, compact, rugged and inexpensive construction.

These and other objects of the invention will more fully appear from the following description made in connection with the accompanying drawing, wherein like reference characters refer to the same or similar parts throughout the views, and in which:

Fig. 1 is a partially broken-away, partially sectional side view of a cane having incorporated therein an embodiment of my invention;

Fig. 2 is a partial longitudinal sectional view drawn to enlarged scale; and

Fig. 3 is a sectional view taken on the line 3—3 of Fig. 2 as indicated by the arrows.

In general my novelty cane has a shank portion consisting of two parts in longitudinally movable telescoped relation to each other, a double acting air pump operated by retraction and projection of one part of the shank relative to the other, and two pneumatically operable sound producing devices connected to the air pump and so arranged that pushing the cane longitudinally against any stationary surface will cause one sound producing device to operate and removing longitudinal pressure on the cane will cause the other sound producing device to operate.

Referring to the drawing my novelty cane includes a shank consisting of a tubular element 4 and an elongated plunger 5 telescoped into the lower end portion of the tubular element 4 in longitudinally slidable relation thereto. The up-

per end of the tubular element 4 is provided with a handle 6 such as shown in Fig. 1 secured thereto by suitable means such as the pin 7. The lower end of the plunger 5 is provided with an enlarged element 8 and a helical spring 9 is placed in concentric encircling relation with the plunger 9 and bears at its respective ends against the enlarged element 8 and the lower end of the tubular element 4. The spring 9 functions to yieldably urge the plunger 9 toward a projected position relative to the tubular element 4. A piston P is provided within the medial portion of the tubular element 4 in sealed longitudinally movable relation therewith. The piston P consists of several parts assembled on the upper end of a rod 10 which at its lower end is screw-threadedly connected to the plunger 9 in co-axial relation with the plunger 9 and the tubular element 4. A piston P includes a pair of pliable cup-shaped washers 11 and 12 which have respective flanges 11a and 12b projecting respectively upwardly and downwardly. The washers 11 and 12 are centrally apertured and are placed in their apertured portions on the upper end of the rod 10 with washers 13 disposed between the pliable washers 11 and 12 above the pliable washer 11 and below the pliable washer 12. Nuts 14 are screw-threadedly mounted on the upper portion of the rod 10 respectively above and below the above described group of washers. The nuts 14 are, of course, tightened to clamp the group of washers therebetween. The piston P constitutes an air displacing member associated with respective air chambers 15 and 16 which consist of portions of the interior of the tubular element 4 respectively above and below the piston P.

At points respectively above and below the portion of the tubular element 4 in which the piston P is moved the tubular element 4 is provided with respective notches 17 and 18 so shaped as to provide respective sharp edges 17a and 18a, each of which is directed toward the portion of the tubular element 4 in which the piston P works. The portions of the tubular element 4 defining the notches 17 and 18 constitute portions of two whistles. A short distance toward the piston P from the respective sharp edges 17a and 18a generally cylindrical blocks 19 and 20 are placed in the interior of the tubular element 4 and are secured therein as by means of screws 21 and 22 projecting through suitable apertures in the tubular element 4 into the respective blocks 19 and 20. The cylindrical blocks 19 and 20 have a small amount of material removed from each thereof to produce flat surfaces 19a and 20a.

20a partially defining restricted passages 23 and 24 communicating with the respective air chambers 15 and 16 and arranged to conduct air therefrom and direct said air against the respective 5 sharp edges 17a and 18a so that air so directed will produce whistling sounds in the manner of ordinary whistles. The lower block 20 is apertured to permit extension of the rod 10 therethrough with freedom for longitudinal movement 10 of the rod 10 with respect thereto.

While the embodiment of my invention illustrated in the drawing and discussed above includes elements forming whistles operated by air pressure developed in the respective chambers 15 and 16, it is obvious that other pneumatically operable sound producing devices may be equally well connected with the respective chambers 15 and 16.

When the cane is pushed against the ground 20 or any other object to move the plunger upwardly relative to the tubular element 4, the piston will be moved upwardly in the tubular element 4 to operate the whistle formed by the sharp edge 17a and the block 19. During this 25 operation air will be sucked in through the lower notch 18 and the whistle formed by the sharp edge 18a and the block 20 will be substantially silent. When the longitudinal pressure on the cane is removed as by lifting upwardly 30 on the handle 6 the plunger 9 and piston P will be moved downwardly relative to the tubular element 4 to force air outwardly through the lower whistle formed by the sharp edge 18a and the block 20. The lower whistle will be operated by 35 this movement of air therethrough and the upper whistle will be substantially silent. The result is that when the cane is pushed longitudinally against a surface and then withdrawn the upper and lower whistles will be operated in succession 40 to produce two non-simultaneous and successive sounds. The respective upper and lower whistles may be made to such relative portions that the successive sounds will be of respectively different pitches. Thus the cane may be readily arranged 45 so that operation thereof will cause the whistles

to produce sounds resembling bird calls, such as the calls of the Bob-White or Cuckoo or any other sounds comprising combinations of two successive notes of respectively different pitches.

It is apparent that I have invented a novel, 5 compact, light, simple, and inexpensive form of novelty cane capable of being easily manipulated to produce non-simultaneous successive sounds of respectively different pitches.

It will, of course, be understood that various 10 changes may be made in the form, details, arrangement and proportions of the various parts throughout the views without departing from the scope of my invention.

What is claimed is:

A novelty cane comprising, a round tubular element of substantial length, a handle mounted on the upper end of said element, a cylindrical plunger slidably telescoped in the lower end of said tubular element, an enlarged ground-engaging head formed on the lower end of said plunger, a helical compression spring closely wound about said plunger and bearing at its respective ends against said head and the lower end of said element, a rod carried by the upper end of said plunger and projecting into the interior of said tubular element in co-axial relation therewith, a piston carried on the upper end of said rod in substantially sealed longitudinally reciprocatable relation with said tubular element, and a pair of 30 plugs secured within said tubular element respectively above and below said piston to establish limits of movement thereof, the lower one of said plugs being apertured to relatively snugly and yet slidably accommodate extension of said rod 35 therethrough, each of said plugs having a portion thereof immediately adjacent one side of the inner periphery of said tubular element cut away to provide an air passage, and said tubular element being apertured at the outer ends of said 40 passages to form in conjunction therewith a pair of whistles operative responsive to respective upward and downward movement of said piston.

EARL H. PITNEY. 45
